UNITED STATES PATENT OFFICE.

WILLIAM C. NELSON, OF ROCHESTER, NEW HAMPSHIRE

CARTRIDGE-SHELL.

1,292,359.

Specification of Letters Patent. Patented Jan. 21, 1919.

Application filed January 17, 1916. Serial No. 72,592.

To all whom it may concern:

Be it known that I, WILLIAM C. NELSON, a subject of King of Sweden, residing at Rochester, in the county of Strafford and 5 State of New Hampshire, have invented certain new and useful Improvements in Cartridge-Shells, of which the following is a specification.

This invention relates to cartridge shells 10 and has for its primary object to provide a cartridge shell whose body is composed of a cartridge shell whose body is composed of fiber.

Another object of the invention is to provide a cartridge shell, the body of which is 15 secured to the head between the slit edges thereof.

A further object of this invention is to provide a cartridge shell which will have the strength of one composed entirely of metal, 20 but which will be materially lighter in weight and therefore much more convenient to transport.

Still another object of this invention is to provide a cartridge shell which will not be a 25 conductor of electricity, making the same much more safe.

With these and other objects in view, this invention consists in the novel construction, combination and arrangement of parts as 30 will be hereinafter described and claimed.

Reference is to be had to the accompanying drawings forming a part of this specification, in which similar reference characters 35 indicate corresponding parts, and in which, Figure 1 is a fragmentary sectional view of a cartridge shell with the head detached.

Fig. 2 is a similar view with the head attached, and

Fig. 3 is a longitudinal sectional view of a 40 small sized cartridge shell.

Although but one size of cartridge shell is hereinafter described, it is understood that this invention may be used in connection with fire arms of different calibers, such as 45 rifles, shot guns, field guns, machine and naval guns. Also the cartridge shell may be made in different tapers and shapes such as "bottle neck" and the like.

Referring to the drawings, 5 indicates the 50 body of the cartridge shell which is composed of hard fiber, which is commonly known as vulcanized fiber, bone or hard fiber. One end of the body is slightly reduced, forming a shoulder 6, and the reduced end is

provided with a plurality of circumferential 55 grooves or recesses 7, the inner walls of which form ribs 8 on the interior of the body, the purpose of which will be more fully described hereinafter.

A metallic cap 9 having an opening 10 for 60 the reception of a fulminating fuse is secured to the body 5. The flange of the head is slit to form the two sections 11 and 12, hereinafter termed the outer and inner walls respectively. The outer wall has on its inner 65 periphery, a plurality of circumferential ribs 13, which are received in the recesses 7 in the body, while the inner periphery of the inner wall is provided with a series of circumferential grooves 14, which receive the 70 ribs 8. An annular slit 15 is formed within the base portion of the cap 9 and provides means whereby the section 11 may be readily bent outwardly.

In assembling the cartridge shell, the head 75 is positioned on the body so that the ribs 8 are received in the recesses 14. In order to make a tight joint therebetween, the inner wall 12 is pressed against the body. Then the outer wall 11 is forced into engagement 80 with the reduced end of the body and the ribs 13 seated in the recesses 7. In this position the edge of the wall 11 rests against the shoulder 6 and thereby assists in limiting the movement of the head on the body. 85

Various changes in the form, proportion and arrangement of parts may be resorted to without departing from the principle or sacrificing any of the advantages of this invention as claimed. 90

Having described my invention what I claim as new and desire to secure by Letters Patent is:

A cartridge shell comprising a cylindrical body having annular exterior recesses forming interior ribs, and a shoulder, a cap having a split, said cap including an inner and outer flange forming a recess for the cylindrical body said recess terminating at the split, the flanges having recesses and ribs 100 respectively for engaging the recesses and ribs of the cylindrical body.

In testimony whereof I affix my signature in presence of two witnesses.

WILLIAM C. NELSON.
